UNITED STATES PATENT OFFICE.

FLOYD E. ERTSMAN, OF CHICAGO, ILLINOIS.

DUMP-WAGON.

1,149,815.

Specification of Letters Patent. Patented Aug. 10, 1915.

Application filed April 2, 1915. Serial No. 18,795.

To all whom it may concern:

Be it known that I, FLOYD E. ERTSMAN, a citizen of the United States, residing at Chicago, Cook county, Illinois, have invented certain new and useful Improvements in Dump-Wagons, of which the following is a specification.

The present invention has reference to certain improvements in dump wagons.

10 It has particular reference to improvements in a dump wagon so constructed that the coal, sand, rock, or other load can be discharged from the rear end of the hopper directly to the desired point of delivery.

15 The dump wagon to which the present invention relates is provided with a hopper portion and with a discharge or delivery portion, the latter being so constructed in some instances that the load can be discharged to a chute at either side of the hopper, or straight down therefrom, as desired.

20 One of the objects of the invention is to so relate the hopper and discharge portions that the load can be delivered in either of 25 the manners, or at either of the points enumerated above.

Another feature of the invention has reference to the construction of the discharge portion itself, whereby the discharge of the 30 load can be most easily controlled. Also to so construct this portion of the wagon that the delivery of the load in either of the manners enumerated can be effected under the control of the operator with a very small 35 number of movable parts related to each other in a very simple manner.

Another feature of the invention has reference to the relative mountings of the hopper and discharge portions so that the entire 40 load can be regularly and continuously discharged merely by manipulation of the hopper itself.

Other objects and uses will appear from a detailed description of the invention which 45 consists in the features of construction and combinations of parts hereinafter described and claimed.

Referring to the drawings: Figure 1 shows a side elevation of a wagon having applied thereto hopper and discharge portions embodying the features of the present invention; Fig. 2 is a rear view of the wagon shown in Fig. 1. In this figure the left hand chute has been released so as to effect 55 a discharge of the load at the left hand

side; Fig. 3 is a section taken on the line 3—3 of Fig. 1 looking in the direction of the arrows, being a section corresponding to the view shown in Fig. 2; Fig. 4 is a view similar to Fig. 3, with the exception that the 60 chutes have been released in such a manner as to discharge the load straight down instead of to one side. Fig. 5 is a face view looking at the central removable plate of the discharge portion; Fig. 6 is a detail of one 65 end of one of the side plates; Fig. 7 is a detail view of the interlocking connection between the central plate shown in Fig. 5, and one of the side plates with which the same co-operates, the central plate in Fig. 7 70 standing in fully released position; Fig. 8 is a detail view corresponding to that of Fig. 7 with the exception that the plates are standing in the position which they normally occupy; and Fig. 9 is a view corresponding to Figs. 7 and 8 with the exception that the central plate is standing in the position which it occupies for the discharge of 75 the load to one side.

In the several figures the wagon frame is 80 designated by the numeral 10. At its rear end it carries the discharge portion 11, and in its central portion it carries the hopper 12. This hopper is pivoted at its lower rear corners 13 so that its front end may be 85 raised upward as shown by the dotted lines in Fig. 1. As a convenient means for lifting the front end of the hopper I have shown the plunger 14 working in the hydraulic cylinder 15, said plunger having a 90 pulley 16 over which passes the lifting cord 17. The front end of this cord is affixed while its rear end is connected to the front portion of the hopper.

The discharge portion 11 comprises essentially the side walls 18 and 19 and the back piece 20. The hopper has its front end 12 closed, but its rear end is open and communicates directly with the discharge portion. The side walls 22 and 23 of the hopper preferably slope down toward its bottom 24, the slope of said side portions being ordinarily greater than the angle of repose of the material of the load. The rear portion of the hopper seats inside of the side 100 walls of the discharge portion as shown in Figs. 3 and 4, working inside of the rear portion when the front end of the hopper is raised. As the lifting operation proceeds the rear edges of the side portions 22 and 23 105 110

of the hopper will approach or tilt down toward the sides 18 and 19, of the discharge portion. This is by reason of the fact that the hopper is pivoted on the line 13. I have, therefore, illustrated the off-sets 25 between the side walls 22 and 23 of the hopper and the side walls 18 and 19 of the discharge portion, the front portions of these off-sets being closed in any desired manner.

10 As the front end of the hopper is raised the load contained therein will slide back and down into the discharge portion. Therefore by simply raising the said front end until the bottom of the hopper reaches 15 the angle of repose of the material, the entire load can be discharged from the hopper. The function of the discharge portion is to receive this material and direct it to one side or the other, or straight down, as 20 desired. I will now describe the particular constructions illustrated for accomplishing these results.

To the lower edges of the sides 18 and 19 of the discharge portion are hinged the side 25 plates 26 and 27, respectively, so that said plates can swing from the positions shown in Fig. 4 to the position shown at the left hand of Fig. 3. The lower part of the discharge portion includes the front and 30 back plates 28 and 29, respectively, between which the plates 26 and 27 are hinged. The plates 28 and 29 are provided with the slots 30 and 31 for the accommodation of the locking pins 32 on the lower ends of the 35 plates 26 and 27. These slots are concentric with the axes 33 on which the plates are hinged.

The rods 34 extend across between the plates 28 and 29 underneath the slots 30 and 40 31; and each of said rods carries a lever 45 at its front end and another similar lever at the back end. Springs 36 connected to the levers 35 at the front ends of the rods tend to swing said levers into the position shown 45 at the right hand side of Fig. 4, so as to maintain the side plates 26 and 27 in the position occupied by the plate 27 as shown in said figure. Also if one of these side plates be in the lowered position, shown in 50 Figs. 2 and 3, it may be swung upward into the position shown in Fig. 4, snapping past the corresponding levers 35 at such time and then being locked in the elevated position. For the purpose of tripping the side plates 55 26 and 27 I have provided the hand levers 37, which are pivoted to the discharge portion at a suitable point, their rear ends being connected to the levers 35 by means of the links 38. Upon depressing the outer end 60 of either of the levers 37 the corresponding side plate will be tripped.

In the lower part of the discharge portion there are pivoted the chute plates 39 and 40, the same being pivoted on the axes 65 41. These chute plates normally stand in

the position illustrated in Fig. 3 where they line up with the corresponding side plates 26 and 27. For this purpose each of the plates 39 and 40 is provided with a bracket 42 which rests on one of the sills 43 of the 70 chassis. These chute plates 39 and 40 can be swung into the vertical position shown in Fig. 4.

Between the lower edges of the side plates 26 and 27 there is supported the central 75 plate 44. This central plate normally stands in the horizontal position between the lower edges of the side plates, filling the gap between the said plates to thereby close in the opening in the discharge portion, and 80 sustaining the load in the wagon. Nevertheless this central plate can be swung down into the position shown in Fig. 3 wherein it alines with the side plate 27 and chute plate 40, or it can be thrown into a similar position in the other direction alining with the side plate 26 and the chute plate 39, or it 85 can be dropped so as to hang straight down as shown in Fig. 4. It thus appears that by throwing the central plate into either one 90 of the three positions enumerated the load can be discharged to either side or straight down, as desired.

The lower edge of each of the side plates is provided with a hooked portion 45 95 throughout its full width. This hooked portion comprises practically a semi-circle. Each end of the central plate 44 has the rounded or beaded portion 46 which tilts easily in the semi-circular hooked portion 45 of the corresponding side plate, so that the central plate can swing down into alinement with either of the side plates as has been previously explained. Opposite to some portion of the length of each of the beaded 100 portions 46 there is a hook 47 occupying substantially ninety degrees of arc, and adapted to travel outside of the corresponding hooked portion 45. Thus the portion 45 lies between the beaded portion 46 and the 105 hooked portion 47.

In examining Fig. 8 it will be apparent that the side plate illustrated therein can swing away from the central plate into the direction of the arrow, whereas the central plate cannot drop straight down. In examining Fig. 9 it will be apparent that when the parts stand in the position there illustrated the central plate cannot pull down away from the side plate in the direction of 110 the arrow. This condition will also remain if the central plate be allowed to hang straight down into the dotted line position shown in Fig. 9. It is thus evident that with this peculiar form of interlocking 115 hinge it is possible for either of the side plates to be dropped down away from the central plate, or it is possible to permit the central plate to swing down about the lower edge of either side plate as an axis, in which 120 125 130

latter case the central plate cannot pull away from the side plate after it has swung past a certain position.

The upper edge of each of the chute plates 5 39 and 40 has the hook portion 48. These hooked portions are so positioned and formed on the chute plates that when the latter stand in their normal positions illustrated in Fig. 3 the lower edge of the central 10 plate will be caught by the one or the other when it is dropped down away from one of the side plates. In this way the lower edge of the central plate will be supported so that the central plate will form a continuation of 15 a side plate and the chute plate corresponding thereto.

When it is desired to bring the plates into the position above described it is only necessary to trip that side plate which is on 20 the side of the wagon to which it is desired to discharge the load. Thereupon the side plate will swing down into the position shown in Fig. 3, releasing the adjacent side of the central plate, and permitting said 25 central plate to fall into the position shown in Fig. 3. This will provide a continuous chute for the discharge of the load at the proper side of the wagon.

When it is desired to discharge the load 30 straight down both of the chute plates 39 and 40 may be turned into the position shown in Fig. 4 wherein their upper edges are spread apart as far as possible and then one of the side plates may be tripped to release the central plate. When this is done 35 the central plate will be permitted to hang straight down from the other side plate, and the load will be discharged straight down between the chute plates.

40 It will be observed from an examination of Fig. 1 that the discharge portion is illustrated as depending from the frame or chassis behind the rear wheels 49. Thus the wagon is of such construction that it can be 45 backed up to a chute or manhole so as to readily discharge the load to any desired point without interference from the frame of the wagon.

While I have herein shown and described 50 only a single embodiment of the features of my invention, still it will be understood that I am in nowise limited to this construction except as I may limit myself in the claims.

I claim:

55 1. In a dump wagon the combination with the frame thereof, of a discharge portion mounted on the rear end of the frame, a hopper having its rear end pivoted to the frame and operatively mounted within the 60 upper end of the discharge portion, side plates hinged to the under side faces of the discharge portion, a central plate having its side edges resting on the lower edges of the side plates, chute plates pivoted within 65 the lower end of the discharge portion and

beneath the side plates, and means for locking the side plates in raised position, substantially as described.

2. In a dump wagon the combination with the frame thereof, of a discharge portion 70 carried by the rear end of said frame, said discharge portion having front and back plates, side plates hinged in the sides of the discharge portion between the front and back plates thereof and having their lower 75 edges adapted to swing downwardly and outwardly away from each other, a central plate of dimensions suitable to occupy the space between the lower edges of the side plates when the side plates are in raised position, means for locking the side plates in 80 raised position, and chute plates pivoted between the front and back plates and beneath the side plates when the same are locked in raised position, substantially as described. 85

3. In a dump wagon the combination with the frame thereof, of a discharge portion mounted on the rear end of said frame, said discharge portion having front and back plates, and having side portions extending 90 between the upper edges of said front and back plates, side plates having their upper edges hinged to the lower edges of said side portions and having their lower edges adapted to swing downwardly and outwardly 95 from each other, means for at times locking said side plates with their lower edges in raised position and with the side plates in alinement with the side portions, chute plates pivoted between the lower portions 100 of the front and back plates and adapted to at times aline with the diagonal opposite side plates and side portions, and a central plate of width suitable to occupy the space between the lower edges of the side plates 105 when said lower edges are sustained in raised position, substantially as described.

4. In a dump wagon the combination with the frame thereof, of a discharge portion mounted on the rear end of said frame, said 110 discharge portion having front and back plates, and having side portions connecting together the upper edges of said front and back plates, side plates, said plates having their upper edges hinged to the lower edges 115 of the side portions, and adapted to have their lower edges swing downwardly and outwardly from each other, means for at times locking said lower edges in raised position, and a central plate of dimensions 120 suitable to occupy the space between the lower edges of the side plates when said side plates are sustained in raised position, substantially as described.

5. In a dump wagon the combination with 125 the frame thereof, of a discharge portion carried by the rear end of said frame, said discharge portion having front and back plates, side portions joining together the upper edges of the front and back plates, 130

- side plates having their upper edges hinged to the lower edges of the side portions and adapted to swing between said front and back plates downwardly and outwardly 5 away from each other, means for at times locking the lower edges of said side plates in raised position, a central plate of dimensions appropriate to occupy the space between the front and back plates and the lower edges of 10 the side plates when said side plates are in raised position, and a hinged connection on each end of said central plate to permit said plate to swing downwardly into a vertical position, hinging about the lower edge of 15 either side plate, substantially as described.
6. In a dump wagon the combination with the frame thereof, of a discharge portion carried by the rear end of said frame and having front and back plates, side portions 20 extending between the upper portions of said front and back plates, side plates mounted between the front and back plates and having their upper edges hinged to said side portions and having their lower edges 25 provided with inturned hooks, means for at times sustaining said lower edges in raised position between the front and back plates, and a central plate of dimensions appropriate to occupy the space between the front 30 and back plates and the lower edges of the side plates when the same are in raised position, the opposite edges of said central plate being provided with transverse slotted

portions of curved formation for the reception of the hooked portions of the side 35 plates, substantially as described.

7. In a dump wagon the combination with the frame thereof, of a discharge portion mounted on the rear end of said frame, said discharge portion having front and back 40 plates, side portions extending between the upper edges of the front and back plates, side plates mounted between the front and back plates and having their upper edges 45 hinged to the side portions, the lower edges of the side plates being provided with in-turned hooks, means for at times sustaining the side plates with their lower edges in raised position, chute plates mounted between the lower portions of the front and 50 back plates and in alinement with the diagonally opposite side plates when the lower edges of said side plates are raised, and a central plate of dimensions appropriate to 55 occupy the space between the front and back plates and the lower edges of the side plates when the side plates are sustained in raised position, the opposite edges of said central plate being provided with curved slots for the reception of the hooked portions of the 60 side plates, substantially as described.
